AUTOMATIC POLISHING MACHINE

Irving H. Russell, Oak Park, Ill., assignor to Sloan
Valve Company, Chicago, Ill., a corporation of
Illinois

Application October 20, 1948, Serial No. 55,477

15 Claims. (Cl. 51—108)

1

This invention relates in general to polishing machines, but more particularly to an automatic machine for progressively polishing and buffing a plurality of work pieces fed into the machine, and the principal object of the invention is to design a new automatic polishing and buffing machine for operating upon work pieces having irregular shaped body contours.

Another object is to provide a new and improved automatic polishing machine in which the work pieces are indexed progressively into different positions at each of which a different polishing operation is performed.

A further object of the invention is to design an automatic polishing machine which is of simple construction, easy to operate and which produces polished surfaces upon work pieces at a high production rate.

Many work pieces, such as valve bodies and the like, are currently produced which have cylindrical contours of different diameters and are usually provided with one or more projecting portions or bosses extending outwardly from the body. In order to polish these valve bodies, it is customary for the workman to manually hold and guide the valve body against the polishing wheel so that all external irregular surface portions are reached by the wheel. This is a costly and time-consuming operation and results in uneconomical production of the valve bodies when large quantities are involved. However, if only a small portion of this manual labor could be dispensed with, substantial savings would be effected. It will likewise be appreciated that where irregular shaped work pieces are involved, many small portions or sections of the body would be inaccessible to the polishing wheels of an automatic polishing machine. These inaccessible portions could continue to be manually polished, while the greater surface portions wherever practical would be automatically processed by the machine.

It is therefore a further object of the invention to provide a machine which will automatically polish as much of the surface of a work piece as it is practical to do so.

With the foregoing and other objects in view, the present invention comprises certain novel constructions, combinations, and operation of parts and elements as will be hereinafter fully described, illustrated in the accompanying drawings, and more particularly pointed out in the appended claims.

Referring to the drawings:

Fig. 1 illustrates a top view of the automatic polishing machine of the invention;

2

Fig. 2 is a sectional side view taken along the line 2—2 of Fig. 1;

Fig. 3 is a cross-sectional top view taken along the line 3—3 of Fig. 4;

Fig. 4 is a cross-sectional side view taken along the line 4—4 of Fig. 1;

Fig. 5 is a partial side view of the polishing mechanism taken along the line 5—5 in Fig. 1;

Fig. 6 is a top view of the work piece and work holder, while

Fig. 7 is a cross-sectional side view taken along the line 7—7 of Fig. 6.

Referring now more particularly to the drawings which illustrate a preferred embodiment of the invention, the mechanism as shown is arranged preferably to "polish" cylindrically-shaped work pieces, but it will be understood throughout the description that this expression is intended broadly to cover other work performing operations, such as grinding and buffing, those operations being necessary prior to nickel or chrome plating the work pieces.

The automatic polishing machine comprises a substantially flat supporting base 5, having a centrally located upright pillar or post 6, carrying on its upper end a rotatable work table or carriage 7, which is journaled in the pillar 6 by sleeve bearing 8; this sleeve being supported by a shoulder of extension 9 of the pillar 6. The work-table 7 is clamped to the shoulder section 9 by means of a clamping nut 11 threaded on an extension 10 of the pillar 6.

Arranged circumferentially around the periphery of the common work-table 7 in spaced relationship is a series of polishing wheels 15 to 20, inclusive, which are located at indexed positions or stations designated by letters B, C, D, E, F and G. There are preferably eight indexed positions to which the work-table 7 can be rotated, station A being the loading and unloading station for the work pieces, while station H is merely an idle station. The polishing wheels are each rotated by individual motors 21 connected by shaft 22 with the motors as seen in Fig. 2. These motors 21 are each supported by angular brackets, such as 23, which in turn are securely attached as by bolts 24 to the base 5 of the polishing machine.

As has been pointed out, the work piece designated generally by reference character 25 is of irregular shape, and in the instance illustrated, is the body of a flush valve, such as is used for flushing water closets. In detail, these valve bodies comprise an upper cylindrical portion 26 (see Figs. 6 and 7) and a lower cylindrical portion 27 of somewhat larger diameter. The upper

cylindrical portion 26 is provided with an outward extending portion 28, usually threaded on the outside while the lower cylindrical portion 27 has a projection 29 internally threaded, and projecting from the opposite side of the valve body 25 from the projection 28. These valve bodies are usually made of brass material and molded in the foundry into the rough casting shape shown. The valve bodies when assembled are usually provided with an interior axial opening for the accommodation of the internal operating mechanism not shown. Advantage is taken of this body opening to provide a means for removably supporting the valve body upon the rotatable work table while the polishing operations are being performed. The valve body is removably supported upon the work table 7 by means of the arbor 30 and the horse shoe washer 31 which is slid under the end 32 of the arbor 30, as will be pointed out hereinafter.

The polishing wheels 15 to 20, inclusive, are preferably arranged opposite each station so as to provide the correct polishing pressure on the work piece surface. The first three polishing wheels 15, 16 and 17, are adapted to perform work only on the lower cylindrical portion 27 of the work piece 25 and each wheel provides a different degree of polishing, for example, the wheel 15 will be for rough polishing, the wheel 16 slightly finer, and the wheel 17 of a still finer polishing construction. The remaining three polishing wheels, 18, 19, and 20, are arranged to perform similar polishing operations upon the upper cylindrical portion 26.

Referring particularly to Figs. 1 and 5, each polishing wheel is adjustably supported by an arrangement including a laterally slideable mounting plate 35 which directly supports the motor by means of bolts 36 screwed into plate 35. This slideable mounting plate 35 is also provided with a pair of rails 37, which are adapted to horizontally slide in channels cut in a vertical plate 38 and formed as a portion of the mounting bracket 23. At the outward end of the plate 38 a turned-up projection 39 carries a hand screw 40 for moving the plate 35 inward and outward with respect to the work table 7, so that the position of the polishing wheels can be varied with respect to the work piece and provide any degree of polishing pressure desired. The hand screw 40 has a spring 41 surrounding its shaft to provide some degree of resiliency with respect to the polishing pressure exerted against the work piece. The end of hand screw 40 threads into a projection 42 of the sliding plate 35, so that the plate may be shifted as desired.

In order to index or rotate the work table 7 successively between the various stations A to H, inclusive, and thereby shift the work pieces progressively, a Geneva intermittent motion is provided. This Geneva motion comprises means for rotating the work table 7 intermittently and cooperates with a depending circular flanged portion 45 on the work table 7, which is arranged with gear teeth 46 on its lower inside surface. The Geneva gear element 47 is coupled directly with a second driving gear 49 adapted to mesh with the large work table gear 46, and is also provided with oppositely disposed slots, such as 50 and 51, adapted to be engaged by a pin 52 at certain intervals. The pin 52 is carried by the disc 53 which is continuously rotated in the direction of the arrow by electric motor 48. The entire Geneva mechanism is suitably supported as shown in Fig. 4 by means of the bracket 54 attached by

screws 55 to the machine base 5. In the well-known manner, operation of motor 48 continually rotates the disc 53, and upon each revolution thereof the pin 52 engages one of the notches 50, effecting a 90 degree rotation of the Geneva gear 47, which in turn rotates its associated gear 49 to thereby revolve the work table 7 clockwise from one of the indexed stations to the next one.

10 Each one of the stations provided for the work pieces has a small gear 58 attached to the work piece arbor 30 below the work table 7, and rotation of this gear 58 consequently effects a similar rotation of the associated work piece. Gears 58 are all meshed with a large driving gear 59, rotatable on the pillar 6 and extension 9, so that rotation of gear 59 will effect a counter clockwise axial rotation of each of the gears 58 at the particular station at which they have been positioned. This axial rotation occurs simultaneously with the polishing operation that takes place upon the work piece in each of the several indexed positions.

For the purpose of controlling the operations 25 of the machine while polishing the work pieces, the hydraulic mechanism illustrated diagrammatically in Fig. 3 is provided. This mechanism and its operation are well known in the art and a detailed illustration is therefore not thought necessary. In its essential elements, the hydraulic mechanism comprises a cylinder 60 having a piston 61 reciprocal therein, which piston has an operating arm 62, extending from it. The cylinder 60 is rigidly supported by a mounting 30 plate 63, fastened to the machine base 5 by bolts as shown in Fig. 4. The free end of operating arm 62 rides in a slot formed in an extension 64 of a pawl and ratchet mechanism for intermittently rotating the large gear 59. This ratchet 35 mechanism includes a bearing plate 65 rotatable on the shoulder formed in the top end of the supporting pillar 6 of the machine. The ratchet teeth 66 are preferably formed integral with the large gear 59, as shown in Fig. 4, and the pawl 40 67 pivoted on plate 65 is adapted to contact successive teeth of the ratchet 66 whenever the extension 64 is given a partial rotation by the piston 61. The arrangement is such that the step by step operation of the pawl 67 and ratchet 66 45 effects a partial rotation of each of the small gears 58 to rotate the work piece axially counter-clockwise for a distance less than a complete revolution.

It will be seen that each of the work pieces 55 upon the work table 7 must be locked upon the arbor 30 whenever polishing operations are performed and means are therefore provided in the loading and unloading station A for releasing this locking means. Referring particularly to Fig. 7, this locking means comprises a mandrel 70, through which the arbor 30 extends, and which has a supporting disc 71 formed on the bottom thereof directly above the surface of the work table 7. The mandrel 70 is further provided with a depending hollow sleeve 72, extending through the work table 7 and keyed as shown to the work piece gear 58. A relatively stiff spring 73 surrounds the arbor 30 and butts against a shoulder 74, formed in the lower end of the arbor 30. A nut 76 and associated washer tightly clamp the mandrel 70 and gear 58 to the work table 7 in the manner shown, the usual bearing being provided to effect smooth rotation of the mechanism described. At the extreme 60 lower portion of the arbor 30 a freely revolving

ball 75 is supported. This ball 75, as the table 7 is indexed, engages a cam surface 77, located directly under the edge of station A. Cam 77 is carried by bracket 78, in turn supported by bolts 79 to the machine base 5, as seen in Fig. 2. 5

The foregoing arrangement is such that whenever the work piece 25 is indexed to station A, the ball 75 is raised on the cam surface 77 against the tension exerted by spring 73. This action forces the arbor 30 upwardly, causing the horse shoe washer 31 to be moved away from the top of the work piece 25, as best seen in Fig. 7. In this position, the work piece 25 is loose upon the mandrel and arbor 30, and the washer 31 may be quickly slipped off and the work piece removed vertically from the arbor 30 and plate 71. In all other indexed positions of the work piece, the spring 73 is effective to rigidly clamp the work piece on the mandrel 7 while polishing operations are taking place and the tension is sufficient to prevent relative rotation of the body and the mandrel. 15

From the description of the mechanism just given, it will be obvious that the polishing operations take place upon the work piece while it is being axially rotated counterclockwise at the stations by the large gear 59 controlled in turn by the hydraulic piston 60, and that the indexing mechanism is effective through the medium of the Geneva gearing 50 to rotate the work table 7 clockwise. There is also another rotation of the gears 58 which takes place during the indexing operation. This is the axial motion occurring when the work table 7 is rotated and indexed clockwise by the internal gear 46 on the work table flange 45 and results in rolling the gears 58 around large gear 59 in a clockwise direction during the indexing movement, as depicted in Fig. 3 by the dotted gear shown between stations B and C. At each station, the gears 58 are rotated in a counterclockwise direction by the clockwise motion of the large gear 59. It is therefore seen that there are three distinct movements effective upon the work pieces. First, when they are axially rotated and polishing operations are being performed upon them; second, when they are radially and bodily moved by the work table from one position to the other, and third, when they are rotated axially during the indexing movement by the gear 46. 45

Referring again to Figs. 1 and 6, it is seen that each of the mandrel discs 71 are provided with a locating arrowhead 80, the purpose of which is to line up the work piece body to enable it to be properly positioned on the mandrel when it is loaded at the loading station A. The work piece body is placed with the lower projecting portion 29 axially in alignment with the indicating arrow 80. When the work piece is now indexed from the loading position A to the first position B, the projecting portion 29 will be in the position as shown in Fig. 1, with the polishing wheel just contacting the beginning of the lower cylindrical portion of the body 27 of the work piece. Since the axial rotation of the work piece at each station is a very slow rate, on the order of one to five R. P. M., it is entirely practical to load and unload the work table at station A while the mandrel 70 is turning. When the work piece body 25 is in station B, it slowly revolves in the direction of the arrow indicated, and the polishing wheel 15 performs its polishing work upon the portion 27 of the body until the body has effected a rotation of approximately 210 degrees, after which it is moved from station B 75

to station C. It will be obvious that for the next polishing wheel 16 to perform its work upon the work piece body, the body must be rotated back again to the same initial starting position in which it contacted the polishing wheel at station B. This retroactive rotation of the work body is performed by rotating the small gear 58 clockwise during the indexing motion by means of the gearing 46 and 58. The work piece therefore arrives at the station C in the correct position to be worked upon again while rotating clockwise with the polishing wheel 16. The same action takes place between the other stations except between stations D and E. 10

In order to effectively correlate the indexing operation with the axial rotation of the work pieces, the electrical circuit diagram and hydraulic mechanism depicted schematically in Fig. 3 is provided. This arrangement includes a hydraulic four-way control valve 86 of well-known construction, the purpose of which is to control the reciprocating motion of the piston 61 within the hydraulic cylinder 60. The hydraulic valve 86 is controlled by an operating lever 87 in turn actuated by a pair of solenoids 88 and 89, which effect the four-way valve operation of valve 86. A hydraulic reservoir or accumulator 90 is also provided together with a pump 91 and a pressure regulator or relief valve 92, all elements being suitably interconnected by hydraulic pressure lines as shown with the lines 93 and 94 from the valve 86 extending into opposite sides of the hydraulic cylinder 60. In order to effect the energization of the solenoids 88 and 89, they are interconnected with a source of electrical current 95, initially closed when desired as by a switch 96. A contact leaf spring 97 is arranged within the rotational path of the cam 56 mounted upon the Geneva motion gear 53. The leaf spring 97 is adapted to close contacts 98 in one position of the cam 56 and contacts 99 in another position of the cam. 20

The foregoing arrangement is such that whenever the switch 96 is closed and the machine set for operation, an electric circuit is closed through this switch and the source of current 95, contacts 97 and 99, to the solenoid 89, energizing the same. As a result, the valve arm 87 is pulled over toward solenoid 89, causing hydraulic fluid to pass over line 93 and force the piston 61 in the right-hand direction in the cylinder 60. This results in the pawl 67 rotating the ratchet 66 one step to the right. This movement of piston 61 is accomplished relatively slowly in order that the large gear 59 can axially rotate each of the associated small gears 58 while the polishing operations on the work piece are taking place. During this time Geneva motion pin 52 is rotating in a counter-clockwise direction while cam 56 has its dwell portion in contact with the leaf spring 97, maintaining contact 99 in a closed condition. Eventually the rise portion of the cam 56 engages and moves contact spring 97, opening contacts 99 and closing contacts 98, which is effective to cause energization of the other electromagnet 88 over an obvious circuit. This action causes the hydraulic fluid to pass over the line 94 to the rear side of the piston 61, forcing the piston outward from the cylinder 60 and causing the ratchet 67 to slide backwards over the ratchet tooth 66 to engage the next tooth. The large gear 59 therefore cannot rotate backwards. 30

During the aforesaid return motion of the ratchet mechanism, the pin 52 of the Geneva motion engages the slot 50 of the Geneva wheel 47, 40

This effects a 90 degree rotation of Geneva gear 41, causing gear 49 through ring gearing 46 on the work table 7 to move or rotate the work table in a counter clockwise direction and index the work pieces to the next station. A short time after Geneva pin 52 moves out of engagement with the Geneva slot 51, the contact spring 97 drops off of the rise portion of cam 56, causing the opening of contacts 98 and the closure of contacts 99. This is effective thereupon to again cause the hydraulic cylinder 60 to axially rotate the work pieces in the polishing position.

As has been stated, the first three polishing wheels, 15, 16 and 17, are effective to operate upon the lower body portion 27 of the work piece 25, while the polishing wheels 18, 19 and 20 are effective on the upper body portion 26. Therefore, as seen in Fig. 5, the respective two groups of polishing wheels rotate on different horizontal levels. Due to the fact that one of the work piece projections 28 is located on the opposite side of the body from the projection 29, it is necessary to effect a partial axial shifting of the body when it is indexed between the two groups of polishing wheels, namely, between positions D and E. Since the work piece has been securely clamped in its mandrel in the loading station A and can only be removed or unlocked at that station, a similar releasing means is provided between positions D and E to unlock the body and prevent its rotation by gear 58 rolling around gear 59 during the indexing between the two aforesaid stations. The unlocking action is accomplished by the mechanism illustrated in Figs. 1 and 5, and includes a restraining member 100 arranged between positions D and E, provided with a curved face plate 101, arranged within the orbit of the work piece 25 as it passes between the two stations. The member 100 is adjustably supported by bolts 102 extending through slots and into an angular bracket 103 supported in turn by bolts 104 upon the polishing motor bracket 23. Between the two aforesaid stations and below the work table 7, there is also arranged a cam member 105 adjustably supported by an integral bracket 106 and screws 107 to motor bracket 23.

The arrangement is such that when the ball 75 rides up on cam surface 105, after the work piece leaves polishing wheel 17, the arbor 30 is moved upwardly, releasing the clamping pressure upon the body 25. At this same instant, while the table 7 is rotated and the work piece has made a partial axial rotation of about 180°, the projecting portion 28 of the body engages the face plate 101 and slides along it without axially rotating. An instant before the work piece body 25 reaches station E, and just prior to its engagement with the polishing wheel 18, the ball 75 rides off of cam surface 105 and the work piece body is again clamped tightly to the mandrel 70 by spring 73. At the station E, the projecting portion 28 is now positioned so that the body can be rotated counter-clockwise in the direction of the arrow, and the polishing operation performed on the upper portion 26 of the body. Thereafter, as the work piece is further indexed clockwise, it is rotated each time to its initial starting position before the next polishing wheel. In station H no polishing action takes place on the body, since this location merely occupies the space of the Geneva motion mechanism. When the work piece reaches the position A, it is readily removed since the arbor 30 is then loosened and the washer 31 can be removed, releasing the body. An-

other work piece is thereupon placed on the mandrel 70.

In the preferred form, the machine contemplates a polishing wheel speed of around 2,000 R. P. M., depending upon the type of work required. The indexing speed of the Geneva motion is preferably set so that the movement of the work piece from one station to the other takes place approximately every ten seconds. Depending upon the type of polishing or grinding desired, it is also preferable that the axial rotation of the work piece when in contact with the polishing wheel be approximately on the order of one to five R. P. M.

It is to be understood that the invention contemplates the provision of any number of polishing wheels or stations from that shown and described. Also, it is clear that any other irregular shaped cylindrical body may be worked upon by the machine with simple adjustments to the mechanism. While only a single preferred machine has been illustrated and described, it is desired that the invention be not limited to the precise structure disclosed, but only by the scope of the appended claims.

It will be further understood that whereas I have shown my invention as applied as a polishing or buffing device, it may be applied to a wide variety of different work performing operations and with different tools or working members. For example, whereas I illustrate polishing wheels 15 to 20, it will be understood that I may apply my invention to milling and cutting operations, and in connection with cutting tools.

What is claimed is:

1. In an automatic machine for processing work pieces having irregular body contours, a work table having work piece supporting means arranged at intervals around said table, intermittent driving means for indexing said work table to position said work pieces into different stations, work performing means arranged opposite each station of said work table, a main gear including pawl and ratchet mechanism for axially rotating each work piece at each station while the work performing means is operating upon the work piece, the axial rotation of the work piece being less than one complete revolution, and means for axially rotating said work piece to its initial axial position during the time said work piece is being indexed by said work table between stations, said last means comprising an arrangement whereby said intermittent driving means rolls said work piece supporting means along said main gear while said main gear is stationary.

2. In an automatic machine for processing work pieces having irregular shaped body contours, a work table having supporting means for said work pieces arranged at spaced intervals around said work table, means for indexing said work table to position said work pieces progressively into a plurality of different stations, polishing means arranged opposite certain of said stations of said work table, there being a different work performing means at each station, means for effecting a partial axial rotation of each work piece during the time it is at each station whereby said work performing means is effective to perform work upon said work pieces, and means for rotating said work pieces axially in a retroactive direction to their initial axial position as said work pieces are being indexed between the different positions by said work table.

3. In an automatic machine for performing

work upon work pieces having body contours of different size diameters and projecting portions formed in each diameter portion of the body, a work table having supporting means thereon for said work pieces arranged at spaced intervals around said work table, means for indexing said work table to position said work pieces progressively into a plurality of different stations, work performing means arranged at each of said stations except at a loading station, certain of said work performing means arranged to perform work on one diameter of said work pieces and others of said work performing means on the other diameter of said work pieces, means for axially rotating each of said work pieces a partial revolution while the work performing operations are being performed on one diameter of the work piece body, means for axially rotating each work piece back to its initial axial position while the work pieces are being indexed between stations, and means for again axially rotating each work piece after it has been indexed from a certain one of said stations to place the work pieces in position to be worked upon on another diameter of the work piece body.

4. In an automatic machine for performing work upon work pieces having cylindrical shaped bodies of different diameters and a projecting portion extending from each diameter of the body, a work table supporting said work pieces at spaced intervals around said table and having means for indexing said work pieces progressively to a plurality of work stations, work performing means at each station, certain of said work performing means arranged to perform work on one diameter of the work piece body and others of said work performing means on another diameter of said work piece body, means for axially rotating each of said work pieces for a partial revolution at each station while the work performing means is working thereon, means for axially rotating said work pieces in a retroactive direction to their initial position while being indexed between stations, and means arranged between certain of said stations for imparting another axial rotation to said work pieces when the work pieces are indexed between the work performing means of one diameter of the work piece body to the work performing means of the other diameter.

5. In an automatic machine for performing work upon work pieces having bodies of different diameters and with projecting portions formed on each body diameter, means for supporting said work pieces at spaced intervals and for moving them progressively into different work stations, work performing means at each station, certain sets of said work performing means arranged for performing work on one diameter of said work pieces and other sets on the other diameter, means including pawl and ratchet mechanism for axially rotating said work pieces as the work performing means works thereon, means including a Geneva gear means for retroactively axially rotating said work pieces as they are indexed between stations, and means for additionally axially rotating said work pieces as the work pieces are indexed from the set of work performing means working on one body diameter to the set of work performing means on the other body diameter.

6. In an automatic machine for performing work upon work pieces having bodies of different diameters and with projecting portions formed on each body diameter, means for supporting said work pieces at spaced intervals on

said machine, a Geneva gear means for moving said work pieces progressively into different work stations, work performing means effective to work upon one body diameter in certain indexed positions of said work pieces and other work performing means effective to work upon another body diameter in other indexed positions, means including pawl and ratchet mechanism for effecting a partial axial rotation of said work pieces when being worked upon on one body diameter, means for effecting a different partial axial rotation of said work pieces when being indexed to a position to be worked upon on the other body diameter, and means including said Geneva gear means for producing a further partial axial rotation while said work pieces are being indexed between stations.

7. In an automatic machine, a rotatable work table having a plurality of work piece stations spaced around it, work performing means located opposite each work station, a Geneva movement for intermittently indexing said work piece stations to a different one of said work performing means, an individual work rotating gear for each work piece, a common driving gear meshed with all of said work piece rotating gears, intermittent step-by-step mechanism for rotating said driving gear to cause a partial rotation of each work piece against the associated work performing means, means for correlating the operation of said step-by-step mechanism and said Geneva movement, said work piece gears also being rotated retroactively by being rolled around said driving gear by the indexing movement of said work table whereby said work pieces are always rotated back to their initial starting position against each work performing means after a partial rotation against the preceding work performing means.

8. In an automatic machine, a rotatable work table having a plurality of work piece stations spaced around it, each work piece comprising a body having upper and lower cylindrical body portions of different diameters and having a projection on each cylindrical body portion extending from opposite sides thereof, a work performing means located opposite each work station, some of said work performing means operating upon the upper body portion and others upon the lower body portion, a Geneva movement for indexing said work piece stations between different ones of said work performing means, an individual rotating gear for each work piece, a common driving gear meshed with all of said work piece gears, intermittent step-by-step mechanism for rotating said driving gear to cause a partial rotation of each work piece against the associated work performing means, means for correlating the operation of said step-by-step mechanism and said Geneva movement, said work piece gears also being rotated retroactively by being rolled around said driving gear by the indexing movement of said work table whereby said work pieces are always rotated back to their initial starting position against each work performing means after a partial rotation against the preceding work performing means, and means located between the sets of work performing means operating on the upper and lower work piece body portions for changing the initial starting position of the work piece at the next succeeding work performing means.

9. In an automatic machine for processing work pieces having irregular shaped body contours, a work table arranged for axial rotation,

work piece supporting means positioned at intervals around said table, Geneva gear means for indexing said table to position said work pieces at different stations, work engaging tools arranged at each station of said work table, means including a main gear and pawl and ratchet drive means for rotating each work piece against such tools after it is indexed to each station, and means including said Geneva gear for rotating each work piece to its initial position as the work piece is indexed between stations.

10. The structure of claim 9 characterized by and including rotary tools arranged at each station of said work table, and driving means for rotating each said tool during rotation of the work piece at the station.

11. In an automatic machine for processing work pieces, a work table arranged for rotation about a predetermined axis, work piece supporting means positioned at intervals around the table, Geneva gear means for indexing the table to position the work pieces at different stations, work engaging tools arranged at each station, means including pawl and ratchet mechanism for rotating each work piece against such tools after the work piece is indexed to each station, and means including said Geneva gear means for rotating the work pieces as the work pieces are indexed from station to station.

12. In an automatic machine for performing work upon work pieces having cylindrical shaped body contours of different diameters and projecting portions formed in each diameter portion of the body, a work table having supporting means thereon for said work pieces arranged at spaced intervals around said work table, means for indexing said work table to position said work pieces progressively into a plurality of different stations, work performing means arranged at each of said stations except at a loading station, certain of said work performing means arranged to perform work on one diameter of said work pieces and others of said work performing means on the other diameter of said work pieces, means for axially rotating each of said work pieces in one direction for less than a full revolution at each of said stations while the work performing means is performing the work thereon, and means for axially rotating said work pieces in a retroactive direction to their initial position while the work pieces are being indexed between stations whereby

the work performed on each work piece will be started on the body diameter at a place immediately adjacent a projecting portion of the work piece body.

13. The method of performing work upon work pieces having irregular shaped body contours which consists in intermittently moving the work pieces between stations, axially rotating each work piece at a station for less than a full revolution while the work is being performed upon the work piece, and then axially rotating the work piece in a retroactive direction for less than a full revolution to its initial axial position while being moved to another station.

14. The method of performing work upon work pieces having irregular shaped body contours which consists in intermittently moving the work pieces from one work station to another, axially rotating the work piece at each station for less than a full revolution while work is being performed upon the work piece, and then simultaneously axially rotating the work piece in a retroactive direction for less than a full revolution while being moved to the next station.

15. The method of performing work upon work pieces having irregularly shaped contours which consists in positioning a work piece at a station, axially rotating the work piece, at such station, for less than a full revolution, while performing work on the work piece, moving the work piece to another station, while simultaneously rotating it in a reverse direction of rotation for less than a full rotation, and axially rotating the work piece in its original direction of rotation, while performing work upon it at said last mentioned station.

IRVING H. RUSSELL.
